Specification for Design.

Patented Apr. 16, 1918.

Application filed February 15, 1918. Serial No. 217,430. Term of patent 14 years.

To all whom it may concern:

Be it known that I, WILLIAM H. DAY, a citizen of the United States, residing at Milwaukee, county of Milwaukee, State of Wisconsin, have invented a new, original, and ornamental Design for an Electrical-Measuring-Instrument Casing, of which the following is a specification.

This invention relates to a new, original and ornamental design for a casing for electrical measuring instruments, such as ammeters or voltmeters, and the invention con-

sists in the peculiar shape and configuration of the same, substantially as shown in the accompanying drawing forming a part of this specification, in which the casing is shown in perspective, looking toward the front of the casing.

I claim:

The ornamental design for an electrical measuring instrument casing, substantially as shown and described.

WILLIAM H. DAY.
